114 Mary St., Pittsburgh, Pa.

Filed June 30, 1959, Ser. No. 824,057

5 Claims. (Cl. 2—174)

This invention is for a lady's toilet accessory, and more particularly it is for a shield for protecting the eyes when hair spray is being applied.

The invention is applicable to use in both the home and in beauty parlors and is used when the hair is being sprayed, primarily to protect one's eyes, but to incidentally afford protection to the forehead, back of the neck, and apparel. Hair spray is generally sprayed from so-called aerosol containers, and it is temporarily very painful, if not injurious, if it contacts one's eyes. When one is using it herself, she is positioned before a mirror and must of course watch carefully what she is doing. If the spray is being applied in a beauty parlor, one is usually provided with a towel to cover the face, or at least the eyes, while the spray is being applied.

The present invention has for its principal object to provide a protector which can be applied to the head quickly and without disturbing the hair, which has been styled to receive the spray, the protection being of such construction that it will remain in place when applied and encircle the area of the hair to be sprayed while projecting far enough from the hair to prevent the spray from contacting the eyes, but without restricting vision, so that even when one is applying spray to her own hair, she can see what she is doing.

A further object of the invention is to provide a protector which will adapt itself to the usual range of head sizes.

A further object of the invention is to provide a shield of this kind with a replaceable cover so that, in a beauty parlor, a fresh cover may be applied for each customer, and when the device is used in the home, a fresh cover may be applied when needed.

These and other objects and advantages are secured by our invention, as will be more fully apparent from the detailed description thereof in conjunction with the accompanying drawings, in which:

FIG. 1 is a view in the nature of a side elevation showing the manner in which the shield is used;

FIG. 2 is a top plan view of the frame of the device;

FIG. 3 is a side elevation of the frame;

FIG. 4 is a plan view of the complete device;

FIG. 5 is a transverse section in the plane of line V—V of FIG. 4;

FIG. 6 is a transverse section in the plane of line VI—VI of FIG. 4; and

FIG. 7 is a side elevation of a slightly modified form of the device.

The device in its preferred form comprises a frame of wire or plastic or combinations of these materials, and a slip-on cover in the nature of a flattened sleeve of plastic film, paper, fabric, or impregnated fabric, as desired.

The frame comprises a resilient back strip 2 of metal or plastic biased by its inherent resilience to maintain a sharply curved contour. It is here shown as being a strip of rectangular section with the greatest dimension in a normally vertical plane, but it may be of any desired shape, so long as it has the required strength and spring. At each end of the back strip are forwardly-extending curved wing-like loops, one loop being designated 3, and the other 4. Each loop has an inner frame member 5 of plastic or wire, usually round in section, and also somewhat resilient, and an outer frame member 6 of the

2

same material, the inner and outer members converging at their rear ends where they are joined to the end of the back strip, while their forward ends are integrally connected by a curved connector portion 7. The frame 5 is sufficiently rigid that when it is applied to the head it will project laterally in brim-like fashion. The back strip and the inner frame members 5 define an opening 8 which is generally oval and smaller in circumference than the normal head size of an adult person. The free ends of the two looped wings 3 and 4 overlap at the front of the device for a substantial distance, there being perhaps as much as four inches of overlap. The frame is angled in the area where the loops connect to the back strip at an obtuse angle, as best seen in FIG. 3, so 15 that the loops slope upwardly and forwardly from the plane of the back strip. The spread between the inner and outer bars of the loop may vary, but desirably it is of the order of 3½ to 4½ inches.

The cover on the frame, designated generally as 9, comprises a flat sleeve of flexible plastic, such as polyvinyl film or like plastic material, or paper which is thin and tough, cloth, either treated or untreated, or other soft, flexible material which can be slipped endwise onto the frame so as to cover the same and extend completely 20 around the frame. Instead of a continuous sleeve, it may be formed as two curved bag-like elements closed at their forward end and having their open ends meet at the back of the frame. To enhance the appearance and utility, the covering is ruffled at 10 to fit close to the neck, and 25 the covering is preferably "gathered" on the frame to enhance its appearance, while the outer edge 11 may also be ruffled.

To use the device, the user grasps the overlapping ends, holds the device back of her neck, and spreading the ends, 30 brings them forwardly, one at each side of the head below the hair line, and as the ends reach the front of the head they are allowed to close back into overlapping position across the forehead. Due to its inherent resilience the device springs to the proper head size, and the head is gripped firmly enough so that the protector stays in place. The ruffled inner edge of the covering adapts itself to irregularities of the contour of the head and face to give added protection.

The protector is wide enough so that at any angle at 40 which one would be expected to tilt the spray can, the eyes, face and forehead and back of the neck would be protected. The cover, is sufficiently pliable, may droop at the back where the frame has only a single bar, but this will nevertheless protect the back of the neck. The device, however, is not so wide that it interferes with the use of one's arms when her hands are manipulating the can above the hair, nor wide enough to obstruct vision when the user is looking into a mirror. Because of the generous overlap at the front, the protector will be continuous across the forehead, even with persons having larger than normal heads.

In the modification shown in FIG. 7 the device is similar to that shown in FIGS. 1 to 6, and corresponding reference numerals designate corresponding parts, but in 50 this case the back of the cover has an apron-like extension 12 that is extremely useful in beauty parlors where the hair is being washed preparatory to being set and sprayed.

Essentially, therefore, the device comprises two generally half-elliptical parts or wings resiliently urged toward each other by a connection at the rear, and having the front ends overlapped and defining between them an elliptical-shaped opening which, when the device is not in use, is smaller than the head of the wearer, the wings forming with the covering a wide brim that projects out from the head in a direction that is substantially at right angles to the forehead and sides of the wearer's head, and further the device is angled so that with the connect-

ing rear portion horizontal, the wings for the most part slope upwardly and forwardly.

While we have shown and described one preferred embodiment of our invention, it will be understood that this is by way of illustration, and various changes may be made in the construction, arrangement of parts and materials within the spirit of our invention and under the scope of the following claims.

We claim:

1. An eye protector of the class described comprising a frame having a curved single resilient rear band portion that may be flexed transversely of its length, an elongated forwardly-projecting inwardly-curved wing-like loop at each end of said rear band portion, the free ends of said loops being resiliently urged into overlapping relation, 10 the rear band and inner perimeter of the loops defining a generally elliptical opening, and an impervious flexible covering over the loops, the loops extending laterally from the head of the wearer when the protector is placed on the head of the wearer with the head received in the elliptical opening.

2. An eye protector as defined in claim 1 in which the flexible covering is a removable envelope fitted over the wing-like loops.

3. An eye protector for use when applying hair spray comprising an integral frame structure having a single rear connecting band portion from each end of which there extends an elongated wing-like loop which projects forwardly from the ends of the rear connecting band portion and the forward ends of which are curved toward each other and held by the resilience of the frame in overlapping relation with the boundary of the loops and the rear connecting portion defining an elliptical opening, the wing-like loops projecting laterally from one's head in brim-like fashion when his head is fitted into the elliptical opening, and a flexible cover over the frame with the covering for the loops being generally planar to provide a thin brim above the face of the wearer.

10 15 20 25 30 35

4. A shield for use in applying hair spray as defined in claim 3 in which the wing-like loops slope upwardly and forwardly when the connecting portion is in a horizontal position whereby the connecting band portion may be fitted about the lower part of the back of the head of the wearer and the wing-like loops with the covering provide a forwardly and upwardly-sloping brim above the sides and the front of the face of the wearer.

5. An eye protector for use when applying hair spray comprising an integral frame structure having a single rear connecting band portion from each end of which there extends an elongated wing-like loop which projects forwardly from the ends of the rear connecting band portion and the forward ends of which are curved toward each other and held by the resilience of the frame in overlapping relation with the boundary of the loops and the rear connecting portion defining an elliptical opening, the wing-like loops projecting laterally from one's head in brim-like fashion when his head is fitted into the elliptical opening, and a flexible cover over the frame with the covering for the loops being generally planar to provide a thin brim above the face of the wearer, the flexible cover being in the form of a sleeve that is slipped endwise over the frame and is removable therefrom, the inner edge of the sleeve being ruffled to press against the head of the wearer and more effectively close any space between the frame and the head and close any space between the frame and the head of the wearer against the flow of spray therethrough.
